UNITED STATES PATENT OFFICE.

**GUSTAV C. PAHLOW, OF GALESBURG, ILLINOIS, ASSIGNOR TO VICTOR CASKET HARD-
WARE CO., OF GALESBURG, ILLINOIS.**

DESIGN FOR A LUG FOR CASKET HANDLES.

Application filed October 28, 1926. Serial No. 19,506. Term of patent 7 years.

To all whom it may concern:

Be it known that I, GUSTAV C. PAHLOW, a citizen of the United States, residing at Galesburg, in the county of Knox and State of Illinois, have invented a new, original, and ornamental Design for a Lug for Casket Handles, of which the following is a specification, reference being had to the accompanying drawing, forming part thereof.

Figure 1 is a front elevation of a lug for casket handles showing my new design.

Figure 2 is a top plan view thereof.

Figure 3 is an end elevation.

I claim:

The ornamental design for a lug for casket handles, as shown.

GUSTAV C. PAHLOW.
